UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

SWITCH MECHANISM FOR ELECTRIC MOTORS.

Original application filed May 21, 1917, Serial No. 169,997. Divided and this application filed November 5, 1919. Serial No. 335,815.

To all whom it may concern:

Be it known that I, BURTON S. AIKMAN, a citizen of the United States, residing at Milwaukee, in the county of Milwaukee and 5 State of Wisconsin, have invented a certain new and useful Improvement in Switch Mechanism for Electric Motors (Case 30), of which the following is a full, clear, concise, and exact description, reference being 10 had to the accompanying drawings, forming a part of this specification.

This invention relates to switch mechanism for electric motors.

In my copending application Serial No. 15 169,997 filed May 21, 1917, I have described a starting and control system for motor driven compressors which automatically effects the starting and stopping of the motor and the loading and unloading of the compressor 20 and which is particularly characterized by provision for safe-guarding the electrical apparatus as well as the compressor itself against damage which might occur as a result of continued operation under improper 25 working conditions.

The present application is a division of the application above referred to and has to do with the motor switch mechanism forming a part of the control system above 30 outlined. Although the embodiment of the invention disclosed in this application is primarily designed for use in a system of this character, it will be understood that features of the invention hereinafter claimed 35 are capable of a wider and more general use.

One object of the present invention is to provide a switch mechanism especially adapted for use with a control system of the character referred to.

Another object is to provide an improved means for controlling the starting resistance for a motor.

Another object is to provide an improved blow-out for the switch.

Another object is generally to improve the construction and operation of switches of this character.

The accompanying drawings which form 50 a part of the present specification illustrate one embodiment of the present invention.

The figures of the drawings are as follows:

Figure 1 is a front elevation of a switch board attached to a compressor and supporting the motor switch mechanism and connected parts. In this figure some of the parts are shown broken away to better illustrate their construction. 55

Figure 2 is a rear elevation of the switch board. 60

Figure 3 is a side elevation, partly in section, of the switch board. This view is taken from the left in Figure 1.

Figure 4 is a side elevation taken in the direction opposite to that of Figure 3. 65

Figure 5 is a bottom plan view.

Figure 6 is a diagram of the circuit connections for the motor.

The embodiment of the invention herein-after described is designed primarily for use 70 with a polyphase induction motor of the wound rotor type. As diagrammatically illustrated in Figure 6 the circuit from the main lines 10, 11 and 12 through the primary leads 13 of the motor is completed 75 through the main switch 14 whose terminals are connected with the main lines and the primary leads through the leads 15, 16, 17 and 18. The motor secondary circuit includes the secondary leads 19, the starting 80 resistances 20, 21 and 22 and a cut-out switch 23 connected in parallel with the resistances for short circuiting the resistances when the motor has come up to its rated speed. 85

Switches 14 and 23, as well as their operating mechanisms, are preferably removably mounted upon a switch board 9 of any approved type (see Figures 1 to 4). The main switch 14 includes two relatively fixed contacts 24 and 25 and two relatively movable contacts 26 and 27 carried by a cross-head 28 actuated by a plunger 29. The relatively fixed contacts 24 and 25 are electrically connected with suitable terminals 30, and 31 90 mounted upon the rear of the switch board and suitably insulated therefrom. These terminals are connected with the feed wires 15 and 16 joined by separable connectors 32 95 of any preferred type to the line wires 10 100

and 11. The relatively fixed contacts 24, and 25 comprise a pivot arm 33 swinging about a shaft 34 and pressed down by a spring 35. Upon the outer end of the arm 5 is mounted an arc receiving contact 36 for making the initial and final contact with the corresponding member of the relatively movable terminals. The conducting or actual switching contact 37 is mounted in 10 back of the arc receiving contact 36 and is adapted to make permanent contact during the time the switch is closed and to carry the necessary current. These contacts 36 and 37 are connected through suitable flexible 15 conductors or straps 38 to the terminals 30, or 31, respectively.

The one main line wire 12 is connected directly to the motor through the lead 39 it being unnecessary to lead this line wire 20 through the switch. The other two primary leads 40 and 41 are connected through suitable connectors 32 to the wires 17 and 18, respectively, which are joined to suitable terminals 43 and 42 upon a pair of lugs 44 and 45 forming a part of the switch operating cylinder 46, the terminals being suitably insulated from the frame of the machine.

The switch operating cylinder 46 is provided with a spring containing housing 47 30 and a pair of stationary wiping contacts 48 and 49 which lie along the side of this housing with plates of insulation 50 and 51 interposed. The plunger 29 hereinabove referred to is actuated by a piston 52 reciprocal in the cylinder 46. The movable contacts 26 and 27 carried by the cross-head 28 are constructed in substantially the same manner as the contacts 24 and 25 except that the same are not yieldably mounted.

40 The cross-head 28 carries a plurality of insulating barriers 53, 54, 55 and 56 which form a pair of arc chambers 57 and 58, for the contact pairs 24-26 and 25-27, respectively. These barriers are spaced apart by 45 suitable insulating collars through which clamping bolts are passed. The movable contacts 26 and 27 are connected by means of movable wipers 59 and 60 to the stationary wipers 48 and 49. It can now be seen that when the contacts 26 and 27 are brought 50 against the contacts 24 and 25, the line wires 10, 11 and 12 will be connected directly to the primary leads 13 of the motor.

The mechanism for actuating the piston 52 of the main switch operating cylinder 46 will now be described.

The cylinder head 61 of the cylinder 46 is provided with a boss 62 which has formed therein a plurality of valve ports and 60 sages, later to be described. The boss is covered by a recessed cap-member 63 comprising a cylinder having a cylinder lining 64 within which slides the cylindrical portion 65 of a valve member 66 having at its 65 upper end an enlarged shoulder or flange 67

bearing a yielding seat 68 which is adapted to engage the rim of the passage member 69. Member 69 forms a valve port communicating with the passageway 70 for a purpose which will be later described. A spring 71 within the member 69 presses against the valve member 66 to yieldably retain the same in its lowermost position as indicated in Figure 3.

The cylindrical portion of the valve member 66 is normally covered by the cylinder lining 64 when the valve member is in its lowermost position. When the valve member is raised however against the action of the spring 71 (see Figure 1) the port 72 effects communication between the chamber 73 within the cap member 63 and a passageway 74 leading to the main switch operating cylinder 46. Chamber 73 is connected by the pipe 75 to any source of fluid pressure.

The spring housing 47 of the cylinder 46 contains a spring 76 interposed between the upper end of the housing and a flange 77 of a hollow sleeve 78. A spring 79 of less strength than the spring 76 is positioned 90 within the sleeve 78 and interposed between an internal flange 80 thereof and the top of the piston 52. These springs act to yieldably retain the piston 52 in its lowermost position as illustrated in Figure 3.

95 Passageway 70 hereinabove referred to communicates with a passageway 81 formed in the switch-board 9 and leading to a pair of arc blow-out nozzles 82 and 83. These nozzles are supported upon the switch-board 100 adjacent the fixed switch contacts 24 and 25 and are designed to blow flat streams of air through the compartments 57 and 58 to extinguish the arcs which might be formed at the time the main switch is opened.

105 The operation of opening and closing the main switch will now be described. When it is desired to close the main switch fluid is admitted under pressure through the pipe 75 to the chamber 73 causing the valve member 66 to be raised to the uppermost position of Figure 1 and thus close off the end of member 69. The fluid under pressure then passes through port 72 and enters the main cylinder 46 by way of the passage 74. This causes the piston 52 to move upwardly 110 against the action of the springs 76 and 79 until the movable contacts 26 and 27 are forced against the fixed contacts 24 and 25, when the main switch is closed. When the pressure in the chamber 73 has been destroyed the valve 66 is forced to return to its lowermost position of Figure 3, thus cutting off communication between passageway 74 and chamber 73 and opening communication 115 between passageway 74 and the interior of member 69. The piston 52 relieved of the air pressure is then forced down by the springs 76 and 79. Due to the greater tension in spring 76 the piston is forced down 120

125 120 The cylinder head 61 of the cylinder 46 is provided with a boss 62 which has formed therein a plurality of valve ports and sages, later to be described. The boss is covered by a recessed cap-member 63 comprising a cylinder having a cylinder lining 64 within which slides the cylindrical portion 65 of a valve member 66 having at its upper end an enlarged shoulder or flange 67

very rapidly at first and then spring 79 acts to move it more gradually during the latter part of its stroke. The air within the cylinder 46 is forced out by the piston through 5 passages 74, 69, 70 and 81 to and through the blow-out nozzles 82 and 83 and extinguishes any arc that might occur.

In applying this switch mechanism to the compressor described in my copending application hereinabove referred to the pipe 75 is connected to a reservoir containing a limited amount of air under high pressure and the valve member 66 is provided with a bleed opening 84 therethrough. This opening permits a leakage of air from the pipe 75 and chamber 73 to the interior of the member 69 when the valve member 66 is in its uppermost position. The main portion of the air from the air reservoir passes from the pipe 75 into the chamber 73 and finally into the cylinder 46 to effect the closing of the main switch in the manner just described. The switch is thus held closed until the pressure in the reservoir, and hence 25 pipe 75, has been depleted due to the escape of the air through the bleed opening 84. At that time the valve member 66 returns to its lowermost position and the piston 52 returns to its lowermost position and reopens 30 the switch, unless some means is provided for preventing such return. Means for this purpose will be later described in connection with the description of the construction and operation of the cut-out switch 23.

35 The cut-out switch is preferably removably mounted on the switch-board near the main switch and includes a pair of relatively fixed contacts 85 and 86 and a pair of relatively movable contacts 87 and 88 constructed in substantially the same manner as the corresponding contacts of the main switch. The fixed contacts 85 and 86 are connected with suitable elongated terminals 89 and 90, respectively, mounted upon and 40 suitably insulated from the rear side of the switch board 9. One end of terminal 89 is connected to a secondary lead from the motor through a feed wire 91 and separable connection 32. The corresponding end of 45 the terminal 90 is similarly connected to another secondary lead through a feed wire 92. The other ends of the terminals are respectively connected to the upper ends of the two compressible resistances 21 and 20 50 by means of flexible conductors 93 and 94. The third secondary lead from the motor is connected to a feed wire 95 which leads up in front of the switch-board and is connected to a terminal 96, as shown in dotted 55 lines in Figure 2. A metallic conductor 97 (Figures 1 and 2) joins this terminal with a terminal 98 extending through the switch-board 9 to the rear thereof which terminal is electrically connected to the upper end of 60 65 the third compressible resistance 22 through the flexible conductor 98'. The lower ends of the three resistances are electrically connected by means of a flexible conductor 99. Thus it will be seen that all three resistances are at all times connected in the secondary motor circuit.

In order to short circuit these resistances the movable switch contacts 87 and 88 are electrically connected to the movable wiper plates 100 and 101, respectively, which are 75 always in contact with the stationary wiper plates 102 and 103. The stationary wiper plates 102 and 103 are electrically connected to the terminals 104 and 105 mounted upon the secondary switch operating cylinder 106. 80 Suitable insulating strips 107 and 108 separate the stationary wiper plates 102 and 103 from the cylinder. Both terminals 104 and 105 are electrically connected to the feed wire 95 through a suitable conductor 109 (see Figures 2 and 4). Thus it will be seen that when the cut-out switch is closed by forcing the movable contacts 87 and 88 against the stationary contacts 85 and 86, respectively, current may pass from the motor through either of the feed wires 90 or 92 across the corresponding switch contacts and through feed wire 95 back to the motor, or vice versa, without passing through the resistance.

The movable switch contacts 87 and 88 are carried by a cross-head 110 supported upon a vertically movable plunger 111 secured to a piston 112 reciprocable in the cylinder 106. A compression spring 113 acts to yieldably retain the piston 112 in the lowermost position of Figure 4. The piston 112, is raised however by the admission of fluid under pressure to the cylinder 106 through the passage 106'. This passage may be connected with any source of fluid pressure through a pipe 114. When the pressure in the cylinder has been reduced the piston 112 is returned to its lower position by the action of the spring 113 and the cut-out switch is reopened. Mechanism is provided for compressing or expanding the resistances 20, 21 and 22 to vary their effective resistance as the cut-out switch mechanism moves toward and from closed position. The mechanism will now be described. A lever 115 is pivotally mounted intermediate its ends as at 116 to the top of the switch-board 9. The forward end thereof projects over the cut-out switch mechanism while the other end engages an insulated stud 117 provided at the upper end of the resistance member 20. Resistance member 20 is supported at its lower end upon one end of a lever 118 pivotally supported as at 119 upon the rear face of the switch-board. The other end of lever 118 serves to support the resistance member 21. (See Figure 2). A similar lever 120 is pivotally mounted as 125 at 121 upon the top of the switch-board 130

above the resistance members 21 and 22. One end of the lever bears against an insulated stud 122 provided at the upper end of the resistance member 21 while the other end bears against an insulated stud 123 provided at the upper end of the resistance member 22. The resistance member 22 is supported at its lower end upon a rigid arm 124 fixed to the switch-board.

10 Sufficient tension is maintained through this system of levers to retain the several resistances in position by a spring means which will now be described. This means includes a telescopic connection between the 15 forward end of lever 115 and an insulating stud or collar 125 secured to and carried by the cut-out switch cross-head 110. The telescopic connection includes a sleeve 126 and a cylindrical member 127 surrounded by a 20 strong compression spring 128. Spring 128 bears at one end against the stud or collar 125 and at the other end against a flange 129 formed on the cylindrical member 127. The cylindrical member is counterbored to receive a small spring 130 which places the 25 system of levers just described under the desired initial tension. The tension of the spring 130 may be adjusted by a set screw 131 to control the value of the starting resistance.

During the upward travel of the cross-head 110 the tension of the spring 128 is gradually materially increased causing a corresponding increase of tension through 30 the system of levers above described. This increased tension effects an equal compression in all of the resistances 20, 21 and 22 thus causing a decrease in their effective resistance to permit a greater flow of current 35 through the motor secondary circuit as the motor speeds up. This decrease in resistance continues until the cut-out switch is closed and the resistances short circuited.

Mechanism is provided for preventing the 40 opening of the main switch until the cut-out switch has been opened and the full resistance thrown into the motor secondary circuit. In stopping, the speed of the motor is thus gradually reduced and the danger of 45 severe arcing at the main switch contacts when this switch opens is avoided. This mechanism includes a latch in the form of a bellcrank lever having a substantially horizontal trip arm 131 and an upright latch arm 132. This lever is pivotally mounted upon the spring housing 47 of the main switch operating cylinder by means of a horizontal pin 133. A spring 134 bearing 50 against the arm 131 tends to move the lever to the latching position shown in Figure 1. The cross-head 28 carries a downwardly and rearwardly projecting rigid arm 135 having a shoulder lug 136 for engagement with the upper end 137 of the latch arm 132 of the 55 lever. As the cross-head 28 reaches its ex-

treme upper position in which the main switch is closed the spring 134 throws the end 137 of the latch arm 132 beneath the lug 136 to retain the switch in closed condition.

The cross-head 110 of the cut-out switch 70 carries a projection 138 which engages the trip arm 131 of the bellcrank lever to trip the lever at the time the cross-head reaches its lowermost position (Figure 4). This releases the cross-head 28 of the main switch 75 permitting the same to drop to open the main switch.

In applying this switch mechanism to the compressor described in my copending application above referred to the pipe 114 is 80 connected to a hydraulic system fed by a pump actuated by the motor so that the pressure of fluid in the passageway 106 is dependent upon the speed of the motor. Thus as the motor, starting from rest, builds 85 up its speed, the piston 112 gradually rises and lifts the cross-head 110. This releases the trip arm 131 permitting the latch arm 132 to lock the main switch closed. Further upward movement of the cross-head 90 gradually reduces the resistances and finally short circuits the resistances by closing the cut-out switch as above described. In order to stop the motor it is necessary to reduce the fluid pressure in the cylinder 106. 95

This is accomplished by the use of an exhaust valve 139 yieldably held to its seat by a spring 140 to close the valve port 141. Spring 140 bears against a piston 143, 100 slideable in a cylindrical portion of a chamber 144 and connected to the valve 139 by a valve stem 145. A small chamber 146 is formed beneath the piston 143 and is connected with a suitable source of fluid pressure through a pipe 147. 105

When it is desired to stop the motor, fluid under pressure is admitted to the chamber 146 through pipe 147 to raise the piston 143 and consequently lift the valve off its seat 110 to open the valve port 141. This permits escape of the fluid from the cylinder 106 and the consequent lowering of the piston 112 to open the cut-out switch. Continued downward movement of the cross-head 110 115 reduces the pressure upon the resistances 20, 21 and 22 so that their effective resistance is increased. Finally the projection 138 on the cross-head strikes the trip arm 131 of the latch mechanism, thus releasing the main 120 switch and permitting the same to open.

The fluid escaping from the switch operating cylinder 106 through the valve port 141 into the chamber 144 may pass out 125 through an exhaust pipe 148. When a lubricating oil is employed as the pressure medium, as in the application above referred to, a passageway 149 may be provided connecting the chamber 144 with the upper end of the cylinder 106 so that as the oil 130

escapes under pressure from the lower end of the cylinder some of it may be forced up into the upper portion of the cylinder above the piston 112 to provide the necessary lubrication for these parts.

Means may be provided for manually closing the main switch in addition to the fluid operated means hereinabove described.

A mechanism for this purpose is illustrated 10 in Figures 1 and 3 and includes a lever 150 pivoted at one end to the front face of the switch-board 9 as at 151. This lever is preferably provided with an anti-friction roller 152 engageable with the end 153 of the rigid 15 arm 135, hereinabove mentioned, secured to the cross-head 28 of the main switch. When it is desired to close the main switch the handle 154 of the lever 150 is raised thus forcing the roller 152 against the rigid arm 20 135 and lifting the cross-head 28 to the switch closing position.

Although the invention has been described in connection with a polyphase induction motor it is clear that it may be employed for 25 controlling motors of various other types.

Various changes may be made in the embodiment of the invention hereinabove described without departing from or sacrificing any of the advantages of the invention as defined in the following claims.

I claim:-

1. In combination a main switch, means for yieldably retaining said switch in one position, means for moving said switch to 35 a second position against the action of said yieldable means, a second switch, and a latch controlled by said second switch for holding said main switch in the second position.

2. In a switch mechanism the combination 40 of a switch having fixed and movable contacts, a single acting cylinder, a piston in said cylinder and connected with said movable contact, means for admitting compressed air to said cylinder, means for depleting the pressure of the live air admitted 45 to said cylinder, means for moving said piston to expel the air from said cylinder and to open said switch, and means for utilizing the air thus expelled to blow out the arc 50 formed during the opening of said switch.

3. In a switch mechanism the combination 55 of a switch having fixed and movable contacts, a single acting cylinder, a piston in said cylinder connected with said movable contact, means for admitting air under pressure to said cylinder to move the piston outwardly to close said switch and to trap the air in said cylinder, a blow-out nozzle connected with said cylinder, and means for 60 moving said piston inwardly in said cylinder to open said switch and to force the air from said cylinder through said blow-out nozzle.

4. The combination of a switch, a switch 65 cylinder, a piston in said cylinder, a fluid

supply passage, a fluid exhaust passage, an arc blow-out nozzle connected with said exhaust passage and a valve for effecting communication either between said cylinder and said supply passage to close said switch or 70 between said cylinder and said exhaust passage to blow out the arc when said switch opens.

5. In combination a mounting board, stationary switch contacts mounted on said 75 mounting board, a movable switch contact, an operating cylinder for said movable contact, a piston movable in the cylinder, a spring for moving the piston to open the 80 switch, jet means for directing a flow of fluid between the stationary contact and the movable contact, a valve and passageways for connecting the cylinder with said jet means when the piston is moved by said 85 spring.

6. In combination a stationary switch contact, a movable switch contact, an arcing chamber surrounding said contacts, a single acting cylinder having an operating piston moved by air pressure for closing said contacts, spring means for opening the contact and expelling the air from the cylinder and means for projecting a jet of air expelled from the cylinder through said arcing chamber when the switch is opened.

7. In combination a switch, an operating cylinder for said switch, a pneumatic blow-out for the switch, a valve mechanism having passages leading to the blowout, to the cylinder and to a source of fluid under pressure, said valve being operated by admission of fluid under pressure to admit fluid under pressure to the cylinder for operating the switch and means to operate the valve to connect the cylinder with the pneumatic 100 blow-out when the switch is opened.

8. In combination a switch, an operating cylinder for closing said switch, a pneumatic blow-out for the switch, a valve mechanism having passageways leading to the 110 cylinder, to the pneumatic blowout and to a source of fluid under pressure, said valve being operated by introduction of fluid under pressure to admit said fluid to the piston to close the switch, said valve having leakage means to permit the fluid under pressure to escape and means for moving the valve to connect the cylinder with the pneumatic blowout when the switch is open.

9. In combination a switch, a blowout 120 nozzle for the switch, an operating cylinder for operating the switch, valve mechanism for said cylinder, said valve mechanism comprising a pair of ports and a movable valve element adapted to obstruct one of 125 said ports at a time, a passage communicating with the cylinder, a passage communicating with the blowout nozzle and one of said ports, a passage communicating with one of said ports and adapted for connec- 130

tion with a source of fluid under pressure, said valve mechanism being actuated by the fluid pressure to admit fluid under pressure to the cylinder, a spring for moving said movable valve elements to connect the cylinder with the blowout nozzle and means for opening the switch.

10. In combination a main switch, a blowout nozzle for said main switch, an operating cylinder for closing said main switch, means for admitting fluid under pressure to said cylinder to close the switch, a mechanical detent for holding said switch in closed position, a spring for moving the piston in said cylinder and to open the switch, a resistance controlling switch adapted to release said detent and valve means for connecting the cylinder with the blowout nozzle.

20. 11. In combination a switch, a blowout nozzle for the switch, a cylinder for closing the switch, a mechanical detent for holding said switch in closed position, a spring for opening said switch, a valve and a conduit 25 for connecting said nozzle with the cylinder to blow out the arc when the switch is allowed to open.

12. The combination of a switch, means for closing said switch including a piston 20 and a single acting cylinder, a pneumatic blow-out connected with said cylinder so that air is forced through said blow-out by the return movement of said piston, and means for opening said switch, including 35 means for effecting a quick movement of said piston at the beginning of its stroke and a slower movement near the end of its stroke.

13. The combination of a switch, a piston 40 and cylinder for actuating said switch, means for admitting fluid under pressure to said cylinder to close said switch, and resilient means connected with said piston for opening said switch including two springs 45 of different strength for effecting a quick initial movement of said piston and a slower final movement of said piston.

14. The combination of a switch, a cylinder, a piston in said cylinder for actuating 50 said switch, means for admitting a limited amount of fluid under pressure to said cylinder to close said switch, and means permitting a leakage of said fluid to effect a reopening of said switch after a predetermined time interval.

15. The combination of a switch, a cylinder, a piston in said cylinder for actuating 60 said switch, means for admitting a limited amount of fluid under pressure to said cylinder to close said switch, a latch for holding said switch closed, and leakage means for depleting the fluid pressure after a predetermined time interval.

16. The combination of a switch, a piston 65 and cylinder for actuating said switch, a

passage for admitting fluid under pressure to said cylinder; an exhaust passage for said cylinder, a valve actuated by the fluid under pressure for effecting communication between said cylinder and said fluid inlet passage, and movable to effect communication between said cylinder and said exhaust passage, and a bleed opening through said valve communicating with said fluid inlet passage and said exhaust passage.

17. The combination of a switch having fixed and movable contacts, a piston and cylinder for actuating said movable contact, means for connecting said fixed contact with a source of electric current, a terminal supported by said cylinder, and an extensible conductor between said terminal and said movable contact including a stationary wiper plate connected with said terminal and a movable wiper plate engaging said stationary plate and connected with said movable contact.

18. In combination a switch, said switch comprising a relatively stationary and a relatively movable contact, an operating cylinder for said switch, a piston rod for said cylinder, said piston rod being connected to the movable contact, said cylinder having a spring housing, said piston rod passing through said housing, a spring in said housing, normally holding said contacts separated, a piston in said cylinder connected to said rod, a stationary wiper plate mounted on the side of said spring housing, and a movable wiper contact carried by said piston rod and connected to said movable contact.

19. In combination a mounting board, stationary and movable contacts mounted on said board, an operating cylinder mounted 105 on said board, a piston rod supporting the movable contact, barrier chambers surrounding the movable and stationary contacts, said barrier chambers being mounted on said piston rod, stationary wiper contacts 110 supported by the cylinder, and movable wiper contacts supported by the piston rod.

20. The combination of a switch, a cylinder, a piston in said cylinder for actuating said switch, a port for admitting fluid pressure to said cylinder to close said switch, an exhaust port of greater capacity than said first named port, and valve mechanism for controlling said ports to effect a closing of said switch or a quick opening of said switch.

21. The combination of a switch, a cylinder, a switch actuating piston in said cylinder and means for admitting fluid to or from said cylinder to actuate said piston, 125 said means being constructed to permit the flow of fluid faster in one direction than the other so as to effect a relatively slow closing of the switch and a rapid opening of the switch.

22. The combination of a switch, a cylinder, a switch actuating piston in said cylinder, a fluid inlet port, a fluid outlet port, fluid means for opening said inlet port and closing said outlet port to close said switch, and means for effecting the opening of said outlet port to open said switch with a quick action.
23. The combination of a switch, a cylinder, a switch actuating piston in said cylinder, a port communicable with said cylinder, a second port of greater capacity than said first named port, and mechanism for opening said first named port to close said switch and for opening said second named port to open said switch with a quick action.
24. The combination of a switch, means for closing said switch and for holding said switch closed for a predetermined period, means operable to hold said switch closed for an indefinite period, and means for effecting the opening of said switch with a quick action when released.
25. The combination of a switch, fluid means for closing said switch and for holding said switch closed for a predetermined period, and means for opening said switch with a quick action after said switch has been released.
26. The combination of a switch and fluid means for closing said switch and for holding said switch closed for a predetermined period, said means including a valve mechanism for effecting a quick opening of said switch after said switch has been released.
27. In combination, a main switch, means for closing the main switch and holding it closed for a predetermined time only, a starting resistance cut-out switch in series with the main switch and means controlled by said latter switch for holding the main switch closed until the latter switch is opened.
28. In combination, a pivoted contact member having an arcing horn and a main contact portion, a cooperating movable switch member having a main contact portion and an arcing horn, means for moving said members into engagement with each other to bring the arcing horns into engagement first and thereafter to bring the main contact portions into engagement, and an arcing chute surrounding said contact members and movable with the second contact member.
29. In combination, a relatively stationary switch member, a relatively movable switch member, a spring tending to separate said members, and pneumatic means operated by said spring for projecting a blast of fluid upon the contact members as they are separated, said movable member having motion for creating said pneumatic pressure before the contacts are separated.
30. In combination, a pair of contact members, one of said members being movable with respect to the other, a spring for moving said movable contact member, and pneumatic means operated by said spring for directing a blast of air upon the contacts when they separate, said movable member having motion prior to separation of the switch members for creating said pneumatic pressure.
31. In combination, a pair of switch members, a single acting cylinder having a piston driven outwardly by fluid pressure for moving one of the members into engagement with the other, a blowout nozzle, means for directing the air driven out of said cylinder by inward movement of the piston upon the contacts as they separate.
32. In combination, a switch having a relatively stationary member, a relatively movable member, a cylinder and piston for moving the movable member into engagement with the stationary member, a spring for moving said piston and movable switch member to open the switch, means for admitting a predetermined quantity of air under pressure to said cylinder and for thereafter exhausting the same, said means directing the air compressed by the return movement of the piston upon the switch members when the switch is opened by said spring.
33. In combination, a switch, a cylinder having a piston for operating said switch, an auxiliary reservoir, means for connecting the auxiliary reservoir to said switch cylinder, and means for bleeding away the pressure of said auxiliary reservoir and switch cylinder.
34. In combination, a switch, a cylinder having a piston for operating said switch, an auxiliary reservoir, means for connecting the auxiliary reservoir to said switch cylinder, and means for bleeding away the pressure of said auxiliary reservoir and switch cylinder, a mechanical detent for holding the switch closed.
35. In combination, a switch, a cylinder having a piston for operating said switch, an auxiliary reservoir, means for connecting the auxiliary reservoir to said switch cylinder, and means for bleeding away the pressure of said auxiliary reservoir and switch cylinder, a mechanical detent for holding the switch closed, and a cut-out switch controlling said mechanical detent.
36. In a switch, a stationary contact member, a relatively movable contact member, a piston, a cylinder, means comprising a source of fluid pressure for moving the piston to close the switch, and means for moving the piston to open the switch, said means comprising a pair of concentric springs, a barrel member connecting the lower end of one spring with the top of the other spring, and a housing for enclosing said springs,

said first spring at its upper end engaging the housing, said piston being adapted to engage the lower end of the barrel whereby the first spring applies its pressure directly to the piston and thereafter the second spring applies pressure to the piston for giving the piston a rapid start but relatively slow travel towards the end of its motion.

37. In a switch, a stationary contact member, a relatively movable contact member, a piston, a cylinder, means comprising a source of fluid pressure for moving the piston to close the switch, and means for moving the piston to open the switch, said means comprising a pair of concentric springs, a barrel member connecting the lower end of one spring with the top of the other spring and a housing for enclosing said springs, said first spring at its upper end engaging the housing, said piston being adapted to engage the lower end of the barrel whereby the first spring applies its pressure directly to the piston and thereafter the second spring applies pressure to the piston for giving the piston a rapid start but relatively slow travel towards the end of its motion, and a blow-out nozzle connected to the cylinder for directing a blast of air upon the switch contact.
38. In combination, a cylinder, a piston, a pair of switch members including a movable member connected to said piston, a pair of springs of different strength for moving the piston inwardly to separate the contact, the stronger spring first applying its pressure directly thereafter through the weaker spring in order to give an additional impulse to the piston for giving a quick operation of the blow-out nozzle, and a blow-out nozzle for directing the air compressed by the inward movement of the piston upon the switch contact when they separate.

39. In combination, a pair of switch members one of said members being movable, a cylinder having a piston connected to said movable switch member, a housing of reduced diameter mounted upon said cylinder, a spring in said housing for opposing the closing movement of the piston, a stationary contact mounted along the side of the housing, and a movable wiper connected to the movable switch member.

40. In combination, a switch having a relatively stationary and a relatively movable member, a spring for throwing the movable member to open position and pneumatic means operated by the spring to project a blast of air between the members as they are separated.

41. The combination of a main switch having means for closing the same, a spring for opening the same, a latch for holding the main switch in closed position, the closing means for the main switch comprising

a cylinder and an auxiliary reservoir for holding the switch closed for a predetermined time only, a latch for holding the switch closed for an indefinite time, and means for tripping out the latch.

42. In combination, a main switch having means for closing the same, a spring for opening the same, a latch for holding the main switch in closed position, the closing means for the switch comprising a piston and cylinder and an auxiliary reservoir for holding said main switch closed for a predetermined time only, a latch for holding the switch closed for an indefinite time, means for tripping out the latch, and a blow-out nozzle connected with the cylinder, the inward movement of the piston under the influence of the spring causing a flow of air through said blow-out nozzle.

43. In combination, a main switch, a blow-out nozzle for the main switch, an operating cylinder for closing said main switch, means for admitting fluid under pressure to said cylinder to close the switch, a mechanical detent for holding the switch in closed position, a spring for moving the piston in said cylinder to open the switch, means adapted to release said detent and valve means for connecting the cylinder with the blow-out nozzle.

44. In an electric controlling device for controlling a motor operated pump, a motor circuit, a circuit changer for said circuit, a pressure cylinder for operating said circuit changer, a valve controlling the admission of pressure to said cylinder, a connection between said valve and said cylinder, and means in said connection for permitting a free flow of fluid out of said cylinder.

45. In an electric controlling device for controlling the electric motor circuit of a motor operated pump, a circuit controller, a pressure actuated motor for actuating the circuit controller, a valve controlling the motor, a connection between the valve and the motor, and means in the connection retarding the flow from the valve to the motor but permitting a free flow from the motor.

46. In an electric controlling device, the combination of a circuit controller, a pressure actuated motor for actuating the circuit controller, a valve controlling the motor, a connection between the valve and the motor, and means in the connection retarding the flow from the valve to the motor and permitting a free flow from the motor.

47. In combination, a switch, a cylinder for closing the switch, a pressure controlled valve, a fluid pressure connection between the valve and the cylinder, and a quick release valve for said cylinder for quick opening of the switch when the pressure in the cylinder decreases below a predetermined value.

48. In combination, a switch having a

contact, a blow-out for the contact, a pressure operated cylinder for closing the switch contact, a spring for opening said contact, a connection for fluid pressure to the cylinder, 5 and a quick release valve for the cylinder for connecting said cylinder with said blow-out.

49. In combination, a switch having a contact, a blow-out for the switch contact, a 10 fluid pressure operated cylinder for closing the switch contact, a fluid pressure connection for the cylinder for closing said switch contact, and a quick release valve connecting the cylinder and the blow-out.

50. In combination, a switch, a fluid pressure operated cylinder for closing the switch, means for admitting a charge of fluid pressure to the cylinder for holding it closed for a predetermined time, a leakage port for dissipating said charge, and a quick release valve for permitting the switch to open quickly after the fluid pressure has been depleted to a predetermined point.

51. In combination, a switch, a fluid pressure operated cylinder for closing the switch, means for admitting a charge of fluid pressure to the cylinder for holding it closed for a predetermined time, a leakage port for dissipating said charge, and a quick release 20 valve for permitting the switch to open quickly after the fluid pressure has been depleted to a predetermined point, and a blow-out for the switch connected to the cylinder through said quick release valve.

52. In combination, a switch having a stationary and movable contact, a cylinder having a piston connected to the movable contact, a spring for moving the piston and movable contact, a fluid pressure connection 30 for the cylinder, a leakage port tending to deplete the pressure in said cylinder and a quick release valve for said cylinder.

53. In combination, a switch having a stationary and a movable contact, a cylinder 40 for operating the movable contact, means tending to open the movable contact, a fluid pressure connection for the cylinder, and a quick release valve for exhausting the pressure in the cylinder when said pressure 50 drops below a predetermined value.

54. In combination, a switch having a stationary and a movable contact, a cylinder for operating the movable contact, means tending to open the movable contact, a fluid 55 pressure connection for the cylinder, and a quick release valve for exhausting the pressure in the cylinder when said pressure drops below a predetermined value, a blow-out for the switch contact, and a connection 60 between said blow-out and said quick release valve.

55. In combination, a main switch, a cut-out switch, a first fluid pressure operated cylinder for the main switch, a leakage port 65 and a quick acting release valve for said cyl-

inder to promote quick opening of said main switch, a second fluid pressure operated cylinder for the cut-out switch, a leakage port and a quick release valve for said second cylinder to promote quick opening of its 70 switch, and means controlled by said cut-out switch for holding the main switch closed.

56. In combination, a main switch, means for closing said main switch, a cut-out switch, in series with a main switch, means 75 for closing the cut-out switch and means controlled by the cut-out switch for holding said main switch closed, and means controlled by said holding means for automatically opening the main switch.

57. In combination, a main switch, means for closing said switch, a spring for opening said switch, a latch for holding said main switch closed, a cut-out switch in series with a main switch, a spring for opening the 85 second switch, means for holding the second switch closed, said latch for the main switch being tripped by opening of the cut-out switch.

58. In combination, a plurality of switches, means for closing said switches in a predetermined order, means for each switch individually tending to open it, means for holding said switches closed and means controlled by opening of one switch for disabling the holding means of an adjacent switch.

59. In combination, a plurality of switches, means for closing said switches in a predetermined order, means for each switch individually tending to open it, means for holding said switches closed, said means being operable only in a different predetermined order from that of closing the switches.

60. In combination, a first switch, a second switch, means for closing the first switch, means for closing said second switch after the closing of the first switch, spring means for throwing the first switch open 100 automatically, means for throwing the second switch open automatically and holding means for the first switch adapted to be tripped out by the opening of the second switch.

61. In combination, a first switch, a second switch, pneumatic means for closing the first switch, spring means tending to open the first switch, fluid pressure means for closing the second switch, spring means tending 110 to throw the second switch open, mechanical holding means for holding the first switch closed, said holding means being tripped out by opening of the second switch and a valve controlling the opening of the second switch.

62. In combination, a first switch, a second switch, pneumatic means for closing the first switch, spring means tending to throw said switch open, a quick release valve for permitting rapid opening of the first switch,

mechanical detent means for holding the first switch closed, a second switch, fluid pressure means for closing the first switch, spring means tending to open said first switch, a quick release valve for permitting rapid opening of said second switch and means on the second switch controlled by opening of said second switch for tripping out the mechanical holding means for the 10 first switch.

63. In combination, a pair of switches, fluid pressure means for closing the switches in predetermined order and detent means for the switch first closed for compelling 15 opening of the switches in the reverse of said predetermined order.

64. In combination, a pair of switches, fluid pressure means for closing the said switches in a predetermined order, detent 20 means for the switch first closed for compelling opening of the switches in the reverse order, and quick release valves for said fluid pressure means for permitting rapid opening of each of said switches.

65. In combination, a switch, a cylinder 25 having a piston for operating said switch, an auxiliary reservoir, means for connecting the auxiliary reservoir to said switch cylinder, means for bleeding away the pressure of said auxiliary reservoir and said 30 switch cylinder; and means for recharging the auxiliary reservoir when the switch is opened.

66. In combination, a switch, a cylinder having a piston for operating said switch, 35 a main reservoir, an auxiliary reservoir, means for connecting the auxiliary reservoir to said switch cylinder, means for bleeding away the pressure of said auxiliary reservoir and said 40 switch cylinder, a mechanical detent for holding the switch closed, and pressure controlled means governed by the pressure in the main reservoir for tripping said mechanical detent and for recharging said auxiliary reservoir.

In witness whereof I hereunto subscribe my name this 30th day of October, 1919.

BURTON S. AIKMAN.
